FIG. 2

FIG. 3

INVENTOR.

KAY M. GRIER

BY

Carroll Moore

ATTORNEY

UNITED STATES PATENT OFFICE

148,350

DESIGN FOR A ROAD ROLLER

Kay M. Grier, North Hollywood, Calif.

Application January 22, 1946, Serial No. 125,840

Term of patent 7 years

(Cl. D14—3)

To all whom it may concern:

Be it known that I, Kay M. Grier, a citizen of the United States of America and a resident of the city of North Hollywood, in the county of Los Angeles and State of California, have invented a new, original, and ornamental Design for Road Roller, of which the following is a specification, reference being had to the accompanying drawing, forming part thereof.

In the drawing:

Figure 1 is a rear perspective view of a road roller, showing my new design, and

Figure 2 is a front perspective view.

Figure 3 is a top plan view.

I claim:

The ornamental design for a road roller, substantially as shown.

KAY M. GRIER.
